FACADE OF A COMPARTMENTALIZED HOUSING FOR ELECTRIC DEVICES

Ernest M. Bevilacqua, Springdale, and Andrew T. Kostanecki and Eliot Noyes, New Canaan, Conn., assignors to General Electric Company, a corporation of New York

Filed Nov. 2, 1961, Ser. No. 67,354

Term of patent 14 years

(Cl. D26—13)

FIG. 1.

FIG. 2.

FIG. 1 is a front elevation of a facade of a compartmentalized housing for electric devices, showing our new design; and

FIG. 2 is a side elevational view of the facade shown in FIG. 1, the opposite side having substantially the same appearance.

The dominant features of the design are shown in full lines and reside in the arrangement of the front covers of juxtaposed compartments of the housing in a plurality of discrete groups spaced vertically and respectively adjoined by bold, unbroken horizontal margins.

We claim:

The ornamental design for a facade of a compartmentalized housing for electric devices, as shown and described.
